COPING

John H. Goodwin, Pittsburgh, Pa., assignor to
Overly Manufacturing Company, Greensburg,
Pa., a corporation of Pennsylvania

Application August 5, 1949, Serial No. 108,767

9 Claims. (Cl. 72—86)

1

This invention is for a coping for use on the parapet walls of buildings and like places where it is desired to prevent water from soaking down into the wall, and is designed to replace the usual coping stone which is quite commonly used, and to eliminate the need for through wall flashing below the coping stone.

Where a coping stone is used on top of a parapet wall, for example, it is the usual practice to put a through wall flashing on the top of the wall below the coping to exclude the seepage of water downwardly through the wall. Sometimes the flashing is not used, in which case the masonry is relied upon to effect a sufficient stoppage against penetration, but this commonly results in water seeping through the wall and leaching out lime from the mortar, leaving a discoloration on the face of the building. It has been proposed in cheaper constructions to carry the roofing up the interior face of the parapet wall and over the top of the parapet, using tar and roofing paper, but this detracts from the appearance of the wall, adds to the fire hazard, and may be loosened by freezing weather or high winds.

The object of the present invention is to provide a metal coping which is architecturally pleasing, which effectively excludes moisture from the top of the masonry or parapet wall, and which will endure for the life of the metal from which it is made. The coping briefly replaces the need for any through wall flashing.

My invention may be more fully understood by reference to the accompanying drawings, in which:

Fig. 1 is a perspective view of a corner of a parapet wall having my coping applied thereto;

Fig. 2 is a transverse section in the plane of line II—II of Fig. 1; and

Fig. 3 is a vertical section longitudinally of a portion of the parapet wall, the view being in the plane of line III—III of Fig. 2.

According to the present invention, the parapet wall or other masonry over which the coping is to be placed, and which is designated 2, is laid with embedded threaded studs or bolts 3 therein at regular intervals, the threaded ends of these bolts projecting beyond the top of the masonry. The bolts are preferably placed along the longitudinal center line of the building, and the space is rather accurately predetermined.

These bolts serve to anchor the coping to the masonry. The coping includes a transverse channel 4 formed preferably from sheet metal, the channel being generally U-shaped in transverse section, as best shown in Fig. 3. It has a bottom

2

5, the center of which is raised to provide a ridge 6, and through the top of this ridge there is a hole 7 to accommodate the upper end of the stud 3. One of these channels is provided at each point 5 where there is one of the embedded bolts. The channel has side flanges 8, and these flanges, as best seen in Fig. 2, taper in height from the inner face 2a of the parapet wall, having a height at the inner end of the channel slightly greater than the height of the rib 5, while being somewhat higher at that end of the channel which is adjacent the outer edge of the parapet wall. In the drawings, 2a designates the inner face of the parapet wall, and 2b designates the outer face. The bolt 3 passes up through the hole 7 in the ridge at the base of the channel, and a nut 3a is screwed thereon to anchor the channel to the masonry. At each side of the stud 3 the channel is provided with a threaded opening 9, these openings 9 also being made in the top of the ridge 6 in the bottom of the channel.

The end of the channel at the outer face of the wall is curved upwardly, as indicated at 5a, and the end of the channel at the inner face of the wall is turned downwardly as indicated at 5b.

The main body of the coping is formed of metal sheets 10 cut to the proper length. The sheets 10 have a wide, downwardly-turned flange 11 at the outer face thereof, and the lower edge of this flange turns inwardly providing a lip 12 that terminates close to the outer face of the parapet wall. The inner edge of the sheet 10 is bent downwardly, providing a depending flange 13. In Fig. 1 I have shown the structure at the corner of the building where two of the members 10 are miter-cut and soldered or otherwise joined together, but throughout the greater portion of the length of the wall, the sheets are of course straight. The ends of the sheets 10 overhang the flanges 8 of the channels 4, as best shown in Fig. 3, and these overhanging edges of the ends are bent downwardly as indicated at 10' in Fig. 3 to more effectively make a weather-tight joint with the channel. A cap strip 14 which is more than twice as wide as the channel 4, is placed over the top of the channel 4 after the ends have been bent downwardly as indicated at 10' in Fig. 3. This cap strip has holes therein positioned so that screws 15 passing through the cover strip will enter and be screwed into the holes 9 in the bottom ridge of the channel. The cover strip 14 thus serves to form a lap joint between the ends of the two sheets 10, and it also clamps the ends of the sheet against the flanges 8 of the channels 4.

55 In assembling, the wall is prepared to receive

the coping by embedding the bolts therein. The channels 4 are then secured in place in the manner hereinbefore indicated by the studs 3 and nuts 3a. The coping sheets 10, which have previously been bent to form, and which are cut to the required lengths and otherwise prepared for the job, are then laid in position. As each two sheets are put in place, the cap strip 14 is screwed down. The cap strip 14 has a downwardly-turned flange 16 at the front face of the building that is turned inwardly to hook around the lip 12, and it has a downwardly-turned flange 17 at its inner end which is curled up under the flange 13 of the ends of the two sheets 10 which it overlaps, as best shown in Fig. 2. This serves to more securely join the coping sheets to the cap strips, which cap strips are in turn secured to the cross channels.

The taper on the flanges 8 of the cross channel imparts a slope to the top of the coping so that the front or outer edge of the coping is higher than the inner edge. This results in any water falling on the coping draining back onto the roof of the building, instead of falling down the front of the building. The cap strip serves to prevent the leakage of any substantial amount of water adjacent the ends of the sheets 10, but if any water does drive under the cap strip 14, it will flow down the sloped ends 10' of the sheets and drip into the bottom of the channel 4. The ridge 5 at the bottom of the channel in which the bolt and screwed holes are made is above the level of any water which would thus seep into the channel. Any water thus collected in the channel cannot flow down the front of the building, due to the upwardly-turned apron 5a. Such water drains to the back of the wall and flows down the downwardly-turned edge of the channel 5b to drip down onto the roof. Should the screws 15 not be entirely tight, so that water could seep in around them, of which there is only a slight possibility, such water would run down the shanks of the screws 15 and drain from the shanks of the screws down the ridge into the bottom of the trough.

The channels 4 are at reasonably close intervals, determined by the size of the sheets which it is practical to handle, but the best spacing can be determined by the roofer. Excessive distance between channels would permit undesirable sagging of the sheets 10. There is sufficient ventilation under the coping to allow for "breathing," and the evaporation of moisture or elimination of condensate. The coping provides a pleasing and attractive trim or finish, and is as enduring as the metal of which it is made. It is less expensive than stone, and of course flashing under the coping is not required.

While I have shown and described one specific embodiment of my invention, it will be understood that various changes and modifications may be made therein.

I claim:

1. A coping for use on a parapet or like wall comprising a channel member adapted to extend crosswise of the wall on which the coping is to be placed, said channel having side flanges that taper in height from one end to the other, coping sheets adapted to extend along the wall, each having an end resting on and slightly overhanging the flanges of the channels, and a cap strip covering the gap between said ends of the coping sheet and lapping over said ends, said cap strip being secured to the channel, the coping sheets each having a flange that is adapted to lap down

over the front face of the wall, and each having a flange along the inner edge thereof that is adapted to lap down over the inner face of the wall.

2. A coping for use on a parapet or other wall comprising a channel member adapted to be secured to the wall and extend crosswise thereof, said channel being of tapering section from one end toward the other and being adapted to have its maximum height at the outer face of the wall, two coping sheets adapted to extend along the wall having their ends resting on and slightly overhanging the channel whereby the coping sheets are sloped corresponding to the taper of the channel, and a cap strip covering the gap between the ends of the two coping sheets and lapping over said ends, means for securing the capped sheets to the channel, the coping sheets each having one longitudinal edge turned downwardly so as to be adapted to lap over the front face of the wall and each having its other longitudinal edge turned down to be adapted to lap over the rear face of the wall.

3. A coping for use on a parapet or other wall comprising a channel member adapted to be secured to the wall and extend crosswise thereof, said channel being of tapering section from one end toward the other and being adapted to have its maximum height at the outer face of the wall, two coping sheets adapted to extend along the wall having their ends resting on and slightly overhanging the channel whereby the coping sheets are sloped corresponding to the taper of the channel, and a cap strip covering the gap between the ends of the two coping sheets and lapping over said ends, means for securing the capped sheets to the channel, the coping sheets each having one longitudinal edge turned downwardly so as to be adapted to lap over the front face of the wall and having the other longitudinal edge turned down so as to be adapted to lap over the rear face of the wall, the flange on said one edge having its lowermost edge turned inwardly to provide a lip that is adapted to terminate close to the face of the wall whereby the coping is adapted to project beyond the front face of the wall on which it is placed.

4. A coping for use on a parapet or other wall comprising a channel member adapted to be secured to the wall and extend crosswise thereof, said channel being of tapering section from one end toward the other and being adapted to have its maximum height at the outer face of the wall, two coping sheets adapted to extend along the wall having their ends resting on and slightly overhanging the channel whereby the coping sheets are sloped corresponding to the taper of the channel, and a cap strip covering the gap between the ends of the two coping sheets and lapping over said ends, means for securing the capped sheets to the channel, the coping sheets each having one longitudinal edge turned downwardly so as to be adapted to lap over the front face of the wall and having the other longitudinal edge turned down so as to be adapted to lap over the rear face of the wall, the channel having the bottom thereof turned upwardly at the end of maximum height and having the bottom thereof turned downwardly at the other end, whereby any moisture that drains from the said channel drains to the said other end.

5. A coping for use on a parapet or other wall comprising a channel member adapted to be secured to the wall and extend crosswise thereof, said channel being of tapering section from one

end toward the other and being adapted to have its maximum height at the outer face of the wall, two coping sheets adapted to extend along the wall having their ends resting on and slightly overhanging the channel whereby the coping sheets are sloped corresponding to the taper of the channel, and a cap strip covering the gap between the ends of the two coping sheets and lapping over said ends, means for securing the capped sheets to the channel, the coping sheets each having one longitudinal edge turned downwardly so as to be adapted to lap over the front face of the wall and having the other longitudinal edge turned down to be adapted to lap over the rear face of the wall, the channel having the bottom thereof turned upwardly at the end of maximum height and having the bottom thereof turned downwardly at the other end, whereby any moisture that drains from the said channel drains to the said other end, said channel having a ridge down the bottom thereof with a hole extending therethrough to receive a securing stud, the said ridge also having threaded sockets in the top thereof, there being screws passing through the cap strip and threaded into said sockets for securing the cap strip to the channel.

6. A coping structure for use on a parapet wall comprising spaced channel elements adapted to extend crosswise of the wall, said channel elements tapering in height from one end toward the other and adapted to have their maximum height at the outer face of the wall, coping sheets extending from one channel to the next and having their ends supported by and slightly overhanging the channels between which they extend, the taper of the channels imparting a slope to said coping sheets, each coping sheet having an edge that is adapted to project beyond the face of the parapet wall at the front face of the building and having a downwardly-turned flange that is adapted to overlap the front face, the other edge of each of said sheets also being turned downwardly so as to be adapted to overlap the rear face of the wall, cap strips over each channel covering the gap between the ends of two adjoining sheets and overlapping said ends, screws securing each cap strip to the underlying channel, and studs adapted to secure each channel to the wall.

7. A coping structure for use on a parapet wall comprising spaced channel elements adapted to extend crosswise of the wall, said channel elements tapering in height from one end toward the other and being adapted to have their maximum height at the outer face of the wall, coping sheets extending from one channel to the next and having their ends supported by and slightly overhanging the channels between which they extend, the taper of the channels imparting a slope to said coping sheets, one edge of each of the coping sheets being adapted to project beyond the face of the parapet wall at the front face of the building and having a downwardly-turned flange that is adapted to overlap the front face, the other edge of each of said sheets also being turned downwardly so as to be adapted to overlap the rear face of the wall, cap strips over each channel covering the gap between the ends of two adjoining sheets and overlapping said ends, screws securing each cap strip to the underlying channel, and studs adapted to secure each channel to the wall, the bottom of each channel being provided with a ridge raised above the level of

the bottom in which the said screws are engaged and through which the said studs pass.

8. A coping structure for use on a parapet wall comprising spaced channel elements adapted to extend crosswise of the wall, said channel elements tapering in height from one end toward the other and being adapted to have their maximum height at the outer face of the wall, coping sheets extending from one channel to the next and having their ends supported by and slightly overhanging the channels between which they extend, the taper of the channels imparting a slope to said coping sheets, one edge of each of the coping sheets being adapted to project beyond the face of the parapet wall at the front face of the building and having a downwardly-turned flange that is adapted to overlap the said front face, the other edge of each of said sheets also being turned downwardly so as to be adapted to overlap the rear face of the wall, cap strips over each channel covering the gap between the ends of two adjoining sheets and overlapping said ends, screws securing each cap strip to the underlying channel, and studs adapted to secure each channel to the wall, the bottom of each channel being provided with a ridge raised above the level of the bottom in which the said screws are engaged and through which the said stud passes, the cap strip also extending down the flanges at both edges of the sheets.

9. A coping structure for use on a parapet wall comprising spaced channel elements adapted to extend crosswise of the wall, said channel elements tapering in height from one end toward the other and being adapted to have their maximum height at the outer face of the wall, coping sheets extending from one channel to the next and having their ends supported by and slightly overhanging the channels between which they extend, the taper of the channels imparting a slope to said coping sheets, one edge of each of the coping sheets being adapted to project beyond the face of the parapet wall at the front face of the building and having a downwardly-turned flange that is adapted to overlap the said front face, the other edge of each of said sheets also being turned downwardly so as to be adapted to overlap the rear face of the wall, cap strips over each channel covering the gap between the ends of two adjoining sheets and overlapping said ends, screws securing each cap strip to the underlying channel, and studs adapted to secure each channel to the wall, the bottom of each channel being provided with a ridge raised above the level of the bottom in which the said screws are engaged and through which the said stud passes, the cap strip also extending down the flanges at both edges of the sheets, the ends of the coping sheets which overhang the channels being turned downwardly into the channels, the cap strip and screws serving to clamp the ends of the coping sheets against the channel on which they are supported.
